UNITED STATES PATENT OFFICE.

JOHN C. VAN AKEN, OF RIDGWAY, PENNSYLVANIA, ASSIGNOR TO VAN AKEN MANUFACTURING COMPANY, A CORPORATION OF PENNSYLVANIA.

SLED.

1,040,061.

Specification of Letters Patent.

Patented Oct. 1, 1912.

Application filed February 12, 1912. Serial No. 677,086.

To all whom it may concern:

Be it known that I, JOHN C. VAN AKEN, a citizen of the United States, residing at Ridgway, in the county of Elk and State 5 of Pennsylvania, have invented or discovered certain new and useful Improvements in Sleds, of which the following is a specification, reference being had therein to the accompanying drawings.

10 This invention relates to sleds of the type having flexible runners and provided with means for bending said runners laterally for the purpose of steering the sled.

One object of the invention is to produce 15 improved steering means for laterally flexing the runners which will provide for an increased range of movement over similar devices as heretofore constructed without permitting looseness of the parts and without necessitating the use of members other 20 than the usual steering bar which project beyond the normal outline of the sled.

Another object of the invention is to provide an improved construction of framework 25 for supporting the body of the sled from the runners.

These and other objects of the invention, together with means whereby the same may be carried into effect, will best be understood 30 from the following description of one form or embodiment thereof illustrated in the accompanying drawings. It will be understood, however, that the particular construction described and shown has been chosen 35 for illustrative purposes merely and that the invention may be embodied in other forms without departing from the spirit and scope thereof.

In said drawings: Figure 1 is a top plan 40 view, partly broken away, showing the parts in normal position. Fig. 2 is a longitudinal section on the line 2—2, Fig. 1. Fig. 3 is a bottom plan view showing the positions of the parts when the runners have been flexed 45 for the purpose of steering the sled. Fig. 4 is a front elevation partly broken away.

Figs. 5 and 6 are detail perspective views, respectively, of one of the cross pieces and one of the uprights forming parts of the 50 framework. Figs. 7 and 8 are detail sectional views on the lines 7—7 and 8—8 respectively, Fig. 5. Fig. 9 is a detail perspective view of one of the inclined braces constituting parts of the framework. Fig.

10 is a detail sectional view on the line 55 10—10, Fig. 9.

12 denotes the runners which are preferably constructed of steel bars substantially T-shaped in cross section. Said runners extend parallel to one another and are curved 60 upwardly at their forward ends in the usual manner, said forward ends being connected by a cross bar 13 pivoted thereto. The top or body of the sled comprises a suitable platform 14 and a frame composed of side bars 65 15 above and normally parallel to the runners 12 and rigidly connected at their forward ends by a cross-piece 16 immediately above and parallel to the bar 13.

The sled top or body is supported from 70 the runners 12 by a framework comprising cross-pieces 17, uprights 18, and inclined braces 19. The cross-pieces 17 comprise channel bars secured at their outer ends to the side bars 15 and at their central portions 75 to the platform 14. Intermediate the platform 14 and side bars 15 the side flanges of the channel bars 17 are bent inwardly for short portions of their length forming sections 20 which are substantially triangular 80 in cross-section, as shown most clearly in Fig. 8. The uprights 18 also comprise channel bars bent over the channel bars 17 to form downwardly extending legs, the side flanges 21 of said channel bars being cut 85 away, as indicated at 22 in Fig. 6, in order to cause the same to embrace the portions 20 of the bars 17 with a closely engaging fit. The lower ends of each of the legs of the uprights 18 are provided with ears 23 90 for attachment to the upstanding flange of the corresponding runner 12. Each of the braces 19 comprises a bar substantially V-shaped in cross section having at its lower end ears 24 for attachment to the corresponding runner and secured at its upper end, as at 25, to the corresponding side bar 15, preferably by means permitting a slight pivotal movement of said braces with respect to said bar.

100 The platform 14 is preferably formed with a forwardly extending tongue 26 to which is pivoted, as at 27, a link or strap 28 rigidly secured, as by bolts 29 and 30, to a steering bar 31 extending cross-wise of 105 the sled immediately above the side bars 15. The bar 13 is formed with a rearwardly extended portion 32 having a pin and slot

connection with the steering bar 31. To this end, in the preferred construction, the bar 13 intermediate its ends is bent rearwardly to form an elongated U-shaped portion providing between its opposite sides or arms a slot 33 closely engaging the bolt 30, which is extended downwardly for this purpose and is provided at its lower end with a nut 34 and washer 35.

10 36 denotes a bent strap or bracket secured to the under side of the steering bar 31 and acting as a filler-piece between said bar and the portion 32 of the bar 13.

With the construction herein shown and 15 described it will be observed that the lateral movement of the steering bar, and consequently of the runners, is not limited in any way by the angular position of said bar, so that a wide range of movement may be 20 given thereto, inasmuch as the portion 32 of the bar 13 may be extended toward the rear to any desired degree without interference with the sled construction and without presenting an unsightly appearance or 25 projecting beyond the front edge of the sled proper. Moreover, it will be observed that the connection between the steering bar and runners is a positive one in all positions of the parts, so that there is no lost motion 30 whether said steering bar be in its normal central position, as shown in Fig. 1, or in its operated position, as shown in Fig. 3. In all similar sled constructions of which I 35 am aware the lateral movement of the steering bar must, in practical use, be quite limited, since in order to increase the same it is necessary to extend the part connecting the steering bar with the cross bar of the runners to an undesirable extent beyond the 40 front of the sled, and, in some cases to provide a certain amount of play between these parts, in order to accommodate the increased lateral movement, which results in looseness or lost motion when the parts are in their 45 normal position, thereby interfering with the positive and reliable control of the sled at all times. These difficulties have all been obviated by the present invention and a sled produced which is of simple and compact 50 construction and efficient and reliable in its operation.

Having thus described my invention, I claim:

1. A sled comprising, in combination, a top or body, a pair of parallel, laterally flexible runners, a frame supporting said top from said runners and connecting the rearward ends of said top and runners, a bar connecting the forward ends of said runners and having a rearwardly extended portion 55 bodily movable transversely of said top or body, a steering bar having a pivotal connection with said top or body, and means connecting said steering bar with the rearwardly extended portion of said connecting 60 bar, said connecting means being constructed and arranged to permit relative angular and longitudinal movements of said parts and to prevent relative lateral movements thereof. 70

2. A sled comprising, in combination, a top or body, a pair of parallel, laterally flexible runners, a frame supporting said top from said runners and connecting the rearward ends of said top and runners, a bar 75 connecting the forward ends of said runners and having a slotted portion extended rearwardly toward said top or body and bodily movable transversely thereof, a link pivoted to said top or body and extending 80 forwardly therefrom, a steering bar between said top or body and said connecting bar, and bolts rigidly connecting said steering bar and link, one of said bolts being extended to enter the slot in the rearwardly extended portion of said connecting bar. 85

3. A sled comprising parallel, laterally flexible runners, a bar connecting the forward ends of said runners and having intermediate its ends a rearwardly bent, U-shaped 90 portion, a top supported from said runners, a link pivoted to said top, a steering bar, and bolts rigidly connecting said steering bar and link, one of said bolts being extended downwardly and lying between the arms 95 of said U-shaped portion.

In testimony whereof I affix my signature, in presence of two witnesses.

JOHN C. VAN AKEN.
